UNITED STATES PATENT OFFICE

RALPH L. SKINNER, OF DETROIT, MICHIGAN, ASSIGNOR TO SKINNER MOTORS, INC., OF DETROIT, MICHIGAN, A CORPORATION OF DELAWARE

INNER CYLINDER CONSTRUCTION FOR INTERNAL COMBUSTION ENGINES

Application filed April 9, 1931. Serial No. 538,724.

In internal-combustion engines having outer, ported cylinders and inner cylinders inside of, and spaced away from, the outer cylinders, with curved or arcuate, reciprocating 5 valves located between the slightly-separated, concentric cylinders, I have heretofore provided supports for such inner cylinders at their lower ends, the specified supports constituting the sole means for carrying such 10 inner cylinders.

I have also so mounted such cylinders in the supports, the latter being desirably in the form of rings, that the cylinders could be removed upwardly from the engine out of 15 the supports without demounting the latter from the cylinder block.

In such structures, however, difficulty was encountered with respect to failure of the pistons, which work in such inner cylinders, 2 and it was only after much study and investigation that I discovered that the fault or trouble resided in the fact that the lower sections of such inner cylinders, due to the heat imposed on them and on co-operating and 25 adjacent parts while the engine was in service became somewhat oval or distorted in cross-section, instead of maintaining the perfect cylindricity required for satisfactory operating conditions.

Experiments and study developed the unexpected fact that the supporting rings into which the lower, shouldered ends of the cylinders fitted snugly, the close fit being thought necessary for the satisfactory mounting of 30 the cylinders, by reason of changes in their temperature, and possibly due to other factors, tended to become out-of-round, and such rings, which were of substantially greater thickness than the relatively-thin, inner cylinders, in turn, squeezed or compressed such encircled or encompassed cylinders into corresponding out-of-true shapes, with the result that the pistons would not reciprocate properly within them.

This difficulty I have now overcome by loosely mounting the cylinders in the rings, that is, in the new and improved structure incorporating this invention, the inner cylinders, so to speak, "float" on or in their rings, 45 whereby any distortion or deformity which

occurs in the latter, due to heat or otherwise, is not transferred to, or imposed on, the cylinders, thus allowing the latter to preserve their exact, round shape.

Another feature of the invention is the provision of means which, while allowing the lateral play of the inner cylinders referred to, also prevents them from rising under the action of the pistons or valves, unless it is intended that such cylinders shall be demounted by upward withdrawal from the engine.

To enable those acquainted with this art to understand the invention and its accruing benefits, in the accompanying drawings constituting a part of this specification, and to which reference should be made in connection with the following detailed description, a present, desirable or preferred embodiment of the invention has been illustrated, and, for the sake of clearness, the same reference numerals have been employed to designate the like parts throughout the views.

In these drawings,—

Fig. 1 is a central, vertical section through one cylinder of a multi-cylinder, internal-combustion engine embodying or incorporating the present invention;

Fig. 2 is a fragmentary view of the lower portion of one of the outer cylinders and its associated parts, the view representing a fragmentary, vertical section on line 2—2 of Fig. 1;

Fig. 3 is a horizontal section on line 3—3 of Fig. 2, also showing a portion of a second cylinder; and

Fig. 4 is a fragmentary section, on an enlarged scale, of a part of one of the supporting rings and a portion of the inner cylinder mounted on it.

By reference to these drawings, it will be noted that the engine includes an outer, water-jacketed cylinder 11 having inlet and exhaust ports 12 and 13, respectively.

Forming an integral part of, and depending from, the cylinder-block are a pair of curved walls 14 and 15 (Fig. 2) terminating along their upright edges in separated, vertical, marginal ribs or flanges 16, 16, the inner surfaces of such members 14 and 15

90

95

100

being curved and forming direct extensions of the inner surface of the outer cylinder.

By means of screws 17, 17, a continuous ring 18 is demountably fastened on the lower ends of the parts 14 and 15, such ring having a circular extension or flange 19 extending up into the space between the members 14 and 15 and desirably bearing on, and conforming to, their curved, inner surfaces.

10 A stationary, inner cylinder or sleeve 21, whose upper end terminates below the outer cylinder ports 12 and 13, has its lower end loosely accommodated in the ring or support 18 (Fig. 4), the cylinder having an external, 15 circular shoulder 22 bearing and resting directly on the top end of the portion 19 of the ring.

Owing to the sidewise looseness or play 20 between the inner cylinder and its sustaining ring, the latter may change its true, circular shape under the action of the heat imposed on it without modifying the true, round form of its supported cylinder, thus effectually 25 overcoming a fault in the engine which heretofore has been of a puzzling and disconcerting nature.

Two, ported, arcuate or curved, intake and exhaust valves 23 and 24 reciprocate longitudinally of, and between, the outer and 30 inner cylinders 11 and 21, being worked up and down by means of connecting-rods 25 and 26 joined to eccentric or crank shafts 27 and 28 rotated by any approved means and at proper speed to secure the correctly-timed 35 opening and closing of the engine ports.

As is customary in engines of this general type, a power-piston 28 reciprocates in the stationary, inner cylinder 21, being joined to the crank shaft 31 by the usual connecting- 40 rod 32.

At certain times or under some circumstances, the piston or the valves, or both together, may tend to raise the inner cylinder out of its socket in its supporting ring, and 45 to prevent such an occurrence, a screw 33 is used in the ring 18, and it has a smooth, projecting end 34 fitting in a recess or slot 35 in the outer surface of the inner cylinder 21.

From the foregoing, it will be apparent 50 that, if the screw 33 is removed and other portions of the engine detached, the inner cylinder may be demounted upwardly and out through the top of the outer cylinder without detachment of the ring 18 from the 55 casting which supports it by means of the screws 17 and without disturbing the sliding valves and their operating means.

Features of novelty and improvement, other than those of the present invention, illustrated in the drawings, and which need not be referred to here specifically, constitute the subject-matter of my Patent No. 1,830, 136, Nov. 3, 1931.

In this specification and in the drawings, 65 only one embodiment of the invention has

been set forth, but those skilled in this art will readily understand that the invention, as defined by the appended claims, is not restricted to such single embodiment, and changes may be made in the construction without departure from the principles involved, and without the loss or sacrifice of any of the benefits or the advantages which inure from the employment of the invention.

I claim:

1. In an internal-combustion engine, the combination of an outer ported cylinder, an inner cylinder inside of and spaced away from said outer cylinder, valve-means between said cylinders, means to reciprocate said valve-means lengthwise said cylinders, means to support said inner cylinder with play between the two laterally of said inner cylinder, means on said support preventing unintentional ascent of the inner cylinder, and a piston reciprocatory in said inner cylinder.

2. In an internal-combustion engine, the combination of an outer ported cylinder, an inner cylinder inside of and spaced away from said outer cylinder, valve-means between said cylinders, means to reciprocate said valve-means lengthwise said cylinders, a ring loosely surrounding the lower end portion of said inner cylinder, the latter having an external shoulder resting on said ring, a pin in said ring extended into a recess in said inner cylinder to prevent unintentional ascent of the cylinder, and a piston reciprocatory in said inner cylinder.

3. In an internal-combustion engine, the combination of an outer ported cylinder, an inner cylinder inside of, spaced away from, and terminating below the ports of, said outer cylinder, valve-means between said cylinders, means to reciprocate said valve-means lengthwise of said cylinders, means to support said inner cylinder with capacity for play of such inner cylinder laterally thereof, and a piston reciprocatory in said inner cylinder.

4. In an internal-combustion engine, the combination of an outer ported cylinder, an inner cylinder inside of, spaced away from, and terminating below the ports of, said outer cylinder, valve-means between said cylinders, means to reciprocate said valve-means lengthwise of said cylinders, stationary means to support said inner cylinder with the latter loosely fitted therein to allow capacity for lateral play of the inner cylinder, and a piston reciprocatory in said inner cylinder.

5. In an internal-combustion engine, the combination of an outer ported cylinder, an inner cylinder inside of, spaced away from, and terminating below the ports of, said outer cylinder, valve-means between said cylinders, means to reciprocate said valve-

means lengthwise of said cylinders, a stationary ring loosely surrounding the lower end of, and supporting, said inner cylinder with capacity for play of said inner cylinder laterally thereof, and a piston reciprocatory in said inner cylinder.

6. In an internal-combustion engine, the combination of an outer ported cylinder, an inner cylinder inside of, spaced away from, and terminating below the ports of, said outer cylinder, valve-means between said cylinders, means to reciprocate said valve-means lengthwise of said cylinders, a stationary ring loosely surrounding the lower end of said inner cylinder, the latter having an external shoulder resting on said ring thus giving the inner cylinder capacity for lateral play, and a piston reciprocatory in said inner cylinder.

20 In witness whereof I have hereunto set my hand.

RALPH L. SKINNER.
